UNITED STATES PATENT OFFICE.

ETHAN I. DODDS, OF CENTRAL VALLEY, NEW YORK, ASSIGNOR TO KERNER MANUFACTURING COMPANY, OF PITTSBURGH, PENNSYLVANIA, A CORPORATION OF PENNSYLVANIA.

METHOD OF MAKING WHEELS.

1,189,071.

Specification of Letters Patent. Patented June 27, 1916.

Application filed June 29, 1912. Serial No. 706,649.

To all whom it may concern:

Be it known that I, ETHAN I. DODDS, a resident of Central Valley, Orange county, New York, have invented a new and useful 5 Method of Making Wheels, of which the following is a full, clear, and exact description, reference being had to the accompanying drawings, forming part of this specification, in which—

10 Figure 1 is a side elevation, partly in section, of one form of wheel made in accordance with my invention; Fig. 2 is a similar view of another form of wheel; Fig. 3 is a partial side elevation of another form 15 of wheel made in accordance with my invention; Figs. 4 and 5 are plan views of cut blanks from which the wheels shown in Figs. 1 and 2 respectively are formed; Fig. 6 is a partial sectional view through a pair of 20 blanks such as shown in Fig. 4 after they have been bent into shape.

This invention relates to the method of making wheels.

The object of my invention is to provide 25 a method for forming blanks from which wheels can be constructed, which method can readily and cheaply be carried out to form wheels which will be highly efficient, and which can be cheaply constructed.

30 The precise nature of my invention will be best understood by reference to the accompanying drawings, which will now be described, it being premised, however, that various changes may be made without departing from the spirit and scope of my invention as defined in the appended claims.

In Fig. 1 I have shown a wheel which is provided with a hub member 2, to which is connected an arc-shaped strip 3 by means 40 of bolts 4, and connected integral with the strip 3, and extending in a radial direction therefrom, are the spokes 5, which are connected to the rim 6 by means of rivets or bolts 7.

45 The wheel shown in Fig. 3 is constructed from a blank such as is shown in Fig. 4, and in making the wheel just described I take a strip or sheet of metal the proper length and width, and through which I 50 punch holes 8, 9 and 10. I then split the strip along lines as indicated at 11, from the openings 9 to the farthest edge of the sheet. After the strip has been slitted, I

then bend the laterally extending strips along the line 12, and then bend the longitudinally extending strip around a circular form and connect the ends thereof to each other, which forms the member 3, the spokes being formed by the laterally extending strips. Two of these blanks are then placed 55 side by side, as shown in Fig. 6, and the central rings are connected to a hub member, while the outer ends of the spokes are connected to a flange or flanges on the rim of the wheel by means of bolts or rivets passing 60 through the openings 10 in the ends of the spokes. The wheel shown in Fig. 2 is made in a similar manner from a blank shown in Fig. 5.

The wheel shown in Fig. 1 is made from 70 a blank similar to that shown in Fig. 4, with the exception that there are two holes punched in the ends of the spokes, and some of the material is removed from between the spokes when the blank is slotted.

75 The advantages of my invention result from the method of making wheels in which the spokes are integrally formed with an annular hub member; further, from the provision of means for securing an auxiliary 80 hub member to the main hub member and for connecting the outer ends of the spokes to a rim member.

I claim:

1. The method of making wheels, which 85 consists in slitting blanks in a general transverse direction to form slitted blanks each consisting of a longitudinally extending strip having a plurality of strips extending laterally therefrom, then bending the laterally 90 extending strips at approximately right angles to the longitudinally extending strip, then bending the longitudinally extending strip in the form of an arc thus positioning the laterally extending strips at approximately 95 right angles thereto, so that they extend in a radial direction from the arc shaped strip, then taking two of said blanks and connecting them to a hub and a rim; substantially as described.

100 2. The method of making wheels, which consists in slitting blanks in a general transverse direction to form blanks each consisting of a longitudinally extending strip having a plurality of strips extending laterally 105 therefrom, then bending the laterally ex-

tending strips at approximately right angles thereto, then bending the longitudinally extending strip in the form of an arc thus positioning the laterally extending strips so that they extend radially from the arc shaped strip, then taking two of said blanks and forming a hub about the arc shaped strips, and finally securing a rim to the ends

of the radial strips; substantially as described.

In testimony whereof, I have hereunto set my hand.

ETHAN I. DODDS.

Witnesses:

FRED B. SMITH,
ABBIE G. MAY.
